UNITED STATES PATENT OFFICE.

JOHN THOMAS TULLOCK, OF HOUSTON, TEXAS, ASSIGNOR OF ONE-HALF TO ROBERT E. LEE JENKINS, OF HOUSTON, TEXAS.

SWITCH-LOCK.

No. 877,816.

Specification of Letters Patent.

Patented Jan. 28, 1908.

Application filed August 17, 1907. Serial No. 388,976.

To all whom it may concern:

Be it known that I, JOHN THOMAS TULLOCK, a citizen of the United States, residing at Houston, in the county of Harris and State of Texas, have invented certain new and useful Improvements in Switch-Locks, of which the following is a specification.

My invention relates to rail-road switches and has particular reference to switch locking devices.

The object of my invention is to provide a switch lock which shall effectually prevent the accidental displacement or "splitting" of the switch, even though the switch operating mechanism should break or otherwise get out of order.

A further object is, to provide a switch locking mechanism which shall be arranged and operated separately from the switch, and the switch operating mechanism.

A further object is to provide a switch lock as mentioned, which shall be of low cost to manufacture and which may be readily applied to any switch now in use, without making any alterations in said switch or its operating mechanism.

Further objects will appear hereinafter.

With these objects in view, my invention consists in the novel switch lock illustrated in the accompanying drawings and fully described and claimed hereinafter.

My invention will be more readily understood by reference to the accompanying drawings, forming a part of this specification and in which,

Figure 1, is a plan view of a switch equipped with a switch lock embodying my invention in its preferred form, Fig. 2, is a cross sectional view on the line x—x, of Fig. 1, looking in the direction of the arrows, the switch being shown closed, and, Fig. 3, is a similar view illustrating the switch in open position.

Referring to the drawings, 1—1, indicate the through rails, and 2—2, the siding rails; 3 indicates the through switch rail and 4, the siding switch rail; the switch rails 3 and 4, are connected by the usual rods, 5, and are operated by any usual switch operating mechanism as 6. It is between the points of the rails, 3 and 4, that I locate my switch locking device, which is operated independently of the switch and the switch operating mechanism and may be constructed so as to

lock either or both of the switch points in place.

In the drawings, I have illustrated a device which is adapted to lock the rail 3, in position when the switch is closed and the main track open, and which may be thrown to lock the rail, 4, when the switch is open and the main track closed; however, the latter may be dispensed with as it is most essential to lock the switch in closed position in order that the flanges on the wheels of a fast through train shall not open or "split" the switch.

Again referring to the drawings 7, indicates a metal block or plate spiked to the tie between the points of the switch; to the plate, 7, are secured the rods, or arms, 8, having sleeves or bearings 9, at their ends for the pair of rods 10. The rods 10, move freely in the sleeves 9, towards and from the switch points and the ends of the rods are forked as at 11, to engage the flange of the switch rail; the device is operated by a handle or lever 12, which is pivoted as at 13, to the block 7; the lever 12, is connected to the rods 10, by a rod 14, pivotally connected to sockets 15, secured to the rods 10, and passing through, or otherwise suitably connected to the lever; it is evident that instead of the hand lever 12, I may operate the locking device from the switch tower in the same manner as the switch is operated.

The operation of the device is as follows: The switch is first closed in the ordinary manner after which the lever, 12, is thrown into the position shown in Fig. 2; this causes the rods 10, to slide longitudinally in the bearings 9, until their ends impinge against the point of the switch rail, 3. When it is desired to open the switch the lever 12, is first thrown in the opposite direction, withdrawing the rods 10, from contact with the switch, after which the switch may be opened in the usual manner.

Having thus described my invention, what I claim as new and desire to secure by Letters Patent is:

1. In a device of the class described, main rails, siding and switch rails, in combination with means for operating said switch rails and a switch locking device arranged between the points of said switch rails, said locking device comprising a rod, mounted for longitudinal movement, trans-

verrely of the track, to impinge against said switch rail and means for operating said rod, substantially as described.

2. In a device of the class described, 5 main rails, siding and switch rails, in combination with means for operating said switch rails and a switch locking device arranged between the points of said switch rails, said locking device comprising a metal 10 plate secured to the tie between the points of said rails, suitable bearings carried by said plate, a pair of rods mounted in said

bearings for longitudinal movement transversely of the track, a lever mounted on said block and suitable connections between said 15 rod and said lever, substantially as described.

In testimony whereof I have signed my name to this specification in the presence of two subscribing witnesses.

JOHN THOMAS TULLOCK.
